UNITED STATES PATENT OFFICE.

FRED K. LEWIS AND LYNN L. ROATH, OF ASHTABULA, OHIO, ASSIGNEES TO THE ASHTABULA BOW SOCKET COMPANY, OF ASHTABULA, OHIO, A CORPORATION OF OHIO.

BOW SOCKET AND LIKE ARTICLE.

Application filed May 10, 1924. Serial No. 712,440.

In foldable vehicle tops, and more especially such tops for automobiles, which constitute the prevailing type of vehicle at present in use, the top covering proper is supported on a series of bows pivotally attached to the vehicle body on either side or to each other, so as to be capable of being folded into a more or less compact stack along with the cover material. The bows in question are of various construction, but in the prevailing type the respective side members of the bow consist of tapering metal tubes, into the outer, larger ends of which the ends of a U-shaped wooden bow proper are driven, while for the purpose of attachment to the vehicle body or to another bow, so-called "irons" are fitted in the smaller ends of such tubular bow sockets, these irons being suitably apertured to receive the bolts that form the pivot pins at the points of attachment of the bow. In order to possess sufficient strength, such irons are ordinarily made in the form of forgings, thus adding considerably to the manufacturing cost of the bow socket, such cost being further increased by the necessity of brazing or welding the irons to the ends of the tubes. Such irons furthermore add appreciably to the weight of the top structure.

The object of the present invention is to provide a bow socket of the general construction just described in which, however, the necessity for thus fitting the smaller ends of the sockets with separate irons, for the purpose stated, is entirely done away with. Instead the end of the tube itself is so fashioned as to be sufficiently rigid and substantial to carry the entire strain of the load imposed on the assembled bow when attached to the vehicle body, as well as to afford an adequate bearing for the pivot pin that forms the means for thus attaching such bow.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but several of the various mechanical forms in which the principle of the invention may be used.

In said annexed drawing:

Fig. 1 is a side elevation of the smaller end of a bow socket embodying our present improved construction; Fig. 2 is a transverse section of such bow socket as for example a section taken on the plane *a*—*a*, Fig. 1, 60 although save in the matter of diameter it represents the section at any point to the right of such plane, as well as a section taken on the plane *b*—*b*, in the initial state of the socket, i. e., before the corresponding portion of the socket has been flattened, as shown in succeeding figures; Fig. 2^a is a sectional view similar to Fig. 2, but illustrating a slightly modified construction; Figs. 3, 5, 4, 5, 6 and 7 represent sections 70 of the flattened portion of the bow socket illustrated in Fig. 1 and may be regarded as taken on the plane indicated by the line *b*—*b*, just referred to, said figures respectively illustrating different methods of folding the side walls of the original circular socket tube in order thus to give the latter desired flattened form; Fig. 8 is an end elevation of a socket tube prior to its being thus flattened and illustrates a modification in 80 construction whereby the end is closed after the flattening operation; Fig. 9 illustrates the end of the tube shown in Fig. 8 after such flattening operation; Fig. 10 is a broken longitudinal section of such end, the plane 85 of the section being indicated by the line 10—10, Fig. 9; Fig. 11 is a view, similar to that of Fig. 8, but showing still a different construction; Fig. 12 is an end view showing such modified construction of socket tube 90 in its flattened condition; Fig. 13 is a side elevation, similar to that of Fig. 1, but illustrating a special form of bow socket end, viz, one designed to be pivotally attached to another bow socket; Fig. 14 is a section 95 of such last mentioned special form of socket, the plane of the section being indicated by the line 14—14, Fig. 13; Fig. 15 is a side elevation of a socket end specially designed for use in still another situation, 100 i. e., where such end is pivotally attached to a swing arm as in a so-called articulated outrigger bow; Fig. 16 is a transverse section of such last mentioned socket end, the plane of the section being indicated by the line 16—16, Fig. 15; Fig. 17 is a broken side elevation, on a larger scale, of a socket end 105 showing the manner in which a hole of relatively large diameter is provided, such as is required where the socket end is fastened 110

to the body iron of the car; and Fig. 18 is a transverse section of such last mentioned socket end, the plane of the section being indicated by the line 18—18, Fig. 17.

5 Our improved socket comprises a main tubular body 1 (Fig. 2), which will ordinarily be of generally tapering form, as hereinbefore explained. Such body is formed from an elongated piece or strip of 10 sheet metal which is bent into circular form, the juxtaposed edges being secured together by means of a lock seam 2, or in other approved fashion. Depending upon the gauge of the sheet metal employed in making body 15 member 1, it may be desirable to reinforce the tube with one or more liners 3, one such liner only being illustrated. This liner, like body member 1, is formed of sheet metal, bent or rolled into tubular form, but it is 20 unnecessary that it have its juxtaposed edges secured together. On the contrary, a slight clearance will be left between such edges as the result of forcing the liner into close fitting contact with the main tubular body 25 1. Such liner, however, is either formed with a longitudinally extending depression 4, corresponding with the inwardly projecting portion of seam 2 so as to interlock therewith, as shown in Fig. 2, or else such 30 liner is disposed with one edge on each side of the seam (see Fig. 2^a), whereby the same interlocking effect is secured.

It has already been explained that in order to form the smaller end of our bow socket 35 for attachment purposes, whether to the vehicle body or to another bow, the tube is suitably flattened adjacent such end (see Fig. 1). The flattening is preferably graduated, the walls of the tube being brought 40 into the substantially contacting relation, shown in Figs. 3 to 6, inclusive, only at the extremity of the end portion of the tubular socket.

The several figures last referred to illustrate as many different ways in which the metal may be folded for the purpose of thus flattening the tube, it being understood that the walls of the latter will be initially formed with longitudinally extending V-shaped indentations along the lines of the desired folds, following which such ends are passed between rollers or subjected to the action of dies which cause the tube to collapse and assume the desired flat, cross-sectional form. In Fig. 2 the flattened effect is obtained by producing two inwardly directed folds 5 at diametrically opposite points in the tube, these being symmetrically located with respect to seam 2 and becoming gradually shallower as they recede from the extremity of the tube until they entirely disappear at points a trifle to the left of the section line a—a, as shown in said Fig. 1. Otherwise stated, each fold increases 60 gradually in depth as it approaches such

tube extremity. In order that the width of the flattened portion of the tube may not be greater than the diameter of the adjacent unflattened portion, rounded V-shaped lands or extensions 5^a are left projecting on each side between the respective folds 5. In the form shown in Fig. 4, one fold 5, located as just described, is employed, but the second fold 6 is located more closely adjacent such seam 2 so as to lie on one of the flat sides of the finished article instead of in the edge thereof as in the case of such folds 5. In Fig. 5 both folds 6 are in the flat side of the article closely adjacent the seam 2. In Fig. 6 a single fold 7 is employed, the position thereof being similar to that of the fold 6 in Fig. 4, but the tube thus flattened may be of thicker section, and a wood filler 9 may be inserted in order to give additional rigidity. The section is likewise thicker in 85 the case of the construction shown in Fig. 7 where a single deeper fold 8 is formed in the one edge of the tubular body, the section of the latter after being flattened being very nearly as thin as in Figs. 3, 4 and 5. This 90 form of construction is particularly desirable where the end of the bow socket requires to be of curved form. In such case the socket may be bent with the edge having fold 8 on the inside, i. e., the concave side 95 of the curve, or the reverse.

Where the flattened side walls are brought substantially into contact with each other, as shown in Figs. 3, 4 and 5, the end of the socket may be finished off by being rounded 100 to the form shown in Fig. 1, the metal of the main tubular body and the liner, if any, being incidentally compacted together to substantially close off any opening therebetween. A hole 10 may then be drilled 105 through the respective flattened side walls for the purpose of attaching the socket to its proper support. In case the side walls are not brought sufficiently closely together to permit the finished effect in the manner 110 just described, the construction illustrated in Figs. 8 to 12, inclusive, may be employed. The liner 3, it will here be observed, has struck up integrally with its end and adjacent its juxtaposed edges two complementary 115 filler or rather closure elements 11. The form and disposition of these is such that when the tubular body and such liner are collapsed, using two folds 5 in the respective edges of the body just as shown 120 in Fig. 3, these elements 11 may be bent inwardly so as to completely close off the opening between the walls of the tubular body. In Figs. 11 and 12 the filler elements 12 are 125 of different form in order to adapt them similarly to close the end of the socket where the latter is provided with two folds 6 in one of its flat sides adjacent seam 2, as shown in Fig. 5.

Figs. 13 and 14 show the end of a bow 130

socket 15 constructed in accordance with the present invention and specially adapted for attachment, through the medium of a bracket or clamp 16, to another bow socket 17 that constitutes the support for the first socket. In the extended condition of the top in which this particular arrangement of bow sockets is designed to be employed, the sockets will incline with respect to the horizontal and to each other substantially as shown in Fig. 13, and it is desirable that the socket 15 be locked against further downward, i. e. clockwise, movement. With this in view, the hole 18 in such socket end, through which passes the rivet 19 whereby the socket is secured to the clamp 16, is drilled to one side of the median line of such socket and the portion of the tubular body lying on the other side of such median line, instead of being folded inwardly, is flattened so as to project outwardly and form a stop 20 that rests against the base of the clamp 16 when the top is extended.

A somewhat similar effect may be obtained in forming the socket for an outrigger bow where the latter is carried by swing arm pivotally attached to a main supporting bow. A lock joint is here necessary between the inner end of the outrigger bow socket and the corresponding arm. As shown in Figs. 15 and 16, the tubular body that enters into such outrigger bow socket 22 is slightly curved or bent upwardly and the opening 23, through which is passed the pin or rivet 24 that secures such socket end to the swing arm 25, is located to one side of the median line of the socket. As in the previously described construction, the flattened tubular body lying on the other side of such median line forms a stop 26 that is adapted to abut against a shoulder 27 on the swing arm, thereby forming in effect a rule joint. Here, however, the extension that forms such stop is folded inwardly to produce a fold 28, as shown in Fig. 16, instead of being flattened outwardly, and no fold is utilized in the other edge of the flattened tubular body that constitutes the socket end.

In Figs. 17 and 18 we show how a hole of relatively large diameter may be formed in a socket end of our improved type. In the case of the main bow, the sockets that carry the same are attached directly to the vehicle body, and the body iron, by which they are thus carried, ordinarily requires a half inch hole in the socket end. Accordingly, in order to assure an adequate bearing, we drill an opening 30 of desired large diameter in the seamed side of the flattened socket end, i. e., in the side in which is found the seam 2, it being preferred that the flattening be effected by using two folds 5 in the respective edges of the socket just as in the form illustrated in Fig. 3. A comparatively small hole

31 is next drilled in the opposite flat side 65 of the socket end, as shown in dotted outline in Figs. 17 and 18, such hole being co-axial with hole 30. Thereupon the metal surrounding such hole 31 is bent or forced inwardly so as to form the side walls 32 of 70 the completed opening. An adequate bearing surface is thus provided between the socket and the body iron, as is desirable, since in the case of such main bow, substantially the entire weight of the top may 75 require to be carried by such body irons.

From the foregoing description, it will be seen that our improved construction of bow socket is adaptable to fit substantially all the requirements met with in vehicle top 80 assemblies. The necessity for the use of socket irons is thus entirely done away with, while at the same time nothing is sacrificed in the way of rigidity or strength since the flattened ends of the tubular socket body, 85 where folded in the manner hereinbefore described, have been found by actual test to be superior to the old fashioned composite construction. With the proper equipment of dies, moreover, our improved type of bow 90 socket is much less expensive to manufacture than the former construction, while the resulting product presents a neater appearance and is capable of receiving a better 95 finish.

The respective ends of such bow are to all intents and purposes bow-sockets, such as herein described, and may be fashioned integrally from the tube in exactly the same 100 way.

Other modes of applying the principle of our invention may be employed instead of the one explained, change being made as regards the mechanism herein disclosed, provided the means stated by any of the following claims or the equivalent of such 105 stated means be employed.

We therefore particularly point out and distinctly claim as our invention:

1. As a new article of manufacture, a 110 structural member for vehicle tops and the like, comprising a tubular portion and an attachment end having flattened parallel walls with a perforation therethrough and an inwardly directed longitudinal fold excluded from such perforation.

2. As a new article of manufacture, a 115 structural member for vehicle tops and the like, comprising a tubular portion and an attachment end having flattened parallel walls with a perforation therethrough and an inwardly directed longitudinal fold lying in one edge of such flattened portion and excluded from such perforation.

3. As a new article of manufacture, a 120 structural member for vehicle tops and the like, comprising a tubular portion and an attachment end having flattened parallel

- walls with a perforation therethrough and two inwardly directed longitudinal folds outside such perforation.
4. As a new article of manufacture, a structural member for vehicle tops and the like, comprising a tubular portion and an attachment end having flattened parallel walls with a perforation therethrough and two inwardly directed longitudinal folds lying in the edges of such flattened portion and outside such perforation.
5. As a new article of manufacture, a structural member for vehicle tops and the like comprising a metal tube formed adjacent its attachment end with two diametrically opposite, inwardly directed, longitudinal folds, the co-extending wall-portions of such tube intermediate of such folds being pressed together to form flat sides and aligned holes being formed in such sides, one such hole being initially smaller than the other and the metal surrounding such hole being forced inwardly to provide a bearing surface.
- 20 6. As a new article of manufacture, a structural member for vehicle tops and the like, comprising a tubular portion and an attachment end having flattened parallel walls with a perforation therethrough and an inwardly directed longitudinal fold outside such perforation, and a liner within said tubular portion and flattened attachment end.
7. As a new article of manufacture, a structural member for vehicle tops and the like, comprising a tubular portion and an attachment end having flattened parallel walls with a perforation therethrough and two diametrically opposite inwardly directed longitudinal folds outside such perforation, and a liner within said tubular portion and flattened attachment end.
- 45 8. As a new article of manufacture, a structural element for vehicle tops and the like comprising a longitudinally seamed metal tube, a liner fitted tightly within said tube and engaging the seam thereof, said tube and liner being formed adjacent one end with an inwardly directed, longitudinal fold circumferentially spaced from such seam and the co-extending wall-portions of said tube and liner being pressed together to form flat sides, and a closure element integral with the end of said liner and bent inwardly to close any space between such walls, said element being shaped to conform with the seam and fold in said tube.
- 50 9. As a new article of manufacture, a structural element for vehicle tops and the like comprising a longitudinally seamed metal tube, a liner fitted tightly within said tube and engaging the seam thereof, said tube and liner being formed adjacent one end with two diametrically opposite, in-
- wardly directed, longitudinal folds symmetrically located with respect to such seam and the co-extending wall-portions of said tube and liner intermediate of such folds being pressed together to form flat sides, and a closure element integral with the end of said liner and bent inwardly to close any space between such walls, said element being shaped to conform with the seam and the two folds in said tube.
10. As a new article of manufacture, a structural member for vehicle tops and the like, comprising a tubular portion and an attachment end having flattened parallel walls with a perforation therethrough and an inwardly directed longitudinal fold outside such perforation, such fold being of greatest depth at the end and gradually tapering back.
- 15 11. As a new article of manufacture, a structural member for vehicle tops and the like, comprising a tubular portion and an attachment end having flattened parallel walls with a perforation therethrough and an inwardly directed longitudinal fold lying in one edge of such flattened portion and excluded from such perforation, such fold being of greatest depth at the end and gradually tapering back.
- 20 12. As a new article of manufacture, a structural member for vehicle tops and the like, comprising a tubular portion and an attachment end having flattened parallel walls with a perforation therethrough and two inwardly directed longitudinal folds outside such perforation, such folds being of greatest depth at the end and gradually tapering back.
- 25 13. As a new article of manufacture, a structural member for vehicle tops and the like, comprising a tubular portion and an attachment end having parallel walls with a perforation therethrough, there being V-shaped lands between said tubular portion and said attachment end, and two diametrically opposite inwardly directed longitudinal folds lying in the edges of such flattened portion and outside such perforation, such folds being of greatest depth at the end and gradually tapering back.
- 30 14. As a new article of manufacture, a structural member for vehicle tops and the like, comprising a longitudinally seamed tubular portion and an attachment end having flattened parallel walls with a perforation therethrough and an inwardly directed longitudinal fold outside such perforations, and a liner within said tubular portion and attachment end having a depression engaging the same.

Signed by us, this 8th day of May, 1924.
